(57) **CLAIM**

The ornamental design for a changing table, as shown and described.

DESCRIPTION

FIG. 1 is a perspective view of a first embodiment of a changing table showing my new design;

FIG. 2 is a front elevational view thereof;

FIG. 3 is a rear elevational view thereof;

FIG. 4 is a right side elevational view with the left side being a mirror image thereof;

FIG. 5 is a top view thereof;

FIG. 6 is a bottom view thereof;

FIG. 7 is a perspective view of a second embodiment thereof;

FIG. 8 is a front elevational view thereof; and,

FIG. 9 is a right side elevational view with the left side being a mirror image thereof;

The broken line showing of the pad in FIGS. 1 and 7, the handles in FIGS. 1, 2, 4, and 6–9, and the feet in FIGS. 1–4 and 6–9, is for illustrative purposes only and forms no part of the claimed design. The rear, top, and bottom views are identical for each embodiment.
